UNITED STATES PATENT OFFICE.

CHARLES C. HIGGINS, OF WOODMERE, NEW YORK.

WINDOW-LOCK.

No. 900,539.

Specification of Letters Patent.

Patented Oct. 6, 1908.

Application filed March 18, 1908. Serial No. 421,828.

To all whom it may concern:

Be it known that I, CHARLES C. HIGGINS, a citizen of the United States, and a resident of Woodmere, in the county of Nassau and 5 State of New York, have invented a new and Improved Window-Lock, of which the following is a full, clear, and exact description.

My invention relates to window locks, my 10 more particular object being to provide a type of lock in which there are two bolts, one for each sash, these bolts being independent of each other for some purposes and yet working in unison for other purposes.

Reference is to be had to the accompanying drawings forming a part of this specification, in which similar characters of reference indicate corresponding parts in all the figures.

20 Figure 1 is a fragmentary elevation of a window jamb and its accompanying parts, showing my improved lock in position; Fig. 2 is a fragmentary section upon the line 2—2 of Fig. 4, looking in the direction of 25 the arrow and showing how my improved lock is used for the purpose of securing the sashes at different heights by aid of locking strips provided with bolt holes into which one or both of the bolts are inserted; Fig. 30 3 is an enlarged elevation of the lock with the casing removed, this view showing the plate and a lever for actuating the latter, for the purpose of forcing the bolts back, and, if desired, for locking them in their 35 back position by aid of a member controllable at will; Fig. 4 is an enlarged section upon the line 4—4 of Fig. 2, looking in the direction of the arrow and showing how the spring-pressed bolts are adapted to be 40 thrust through the locking strips in order to hold the sashes; and Fig. 5 is a fragmentary plan view of the locking strip removed from its fastenings.

The framework of a window is shown at 45 6 and is provided with facing strips 6^a. The casing 7 is of metal and is provided with ears 7^a integral with it, for the purpose of securing it permanently in position. Locking strips 8, 9, entirely independent of each 50 other, are each provided with a row of bolt holes 10, mating bolt holes 10^a in the sash 13, and held in position by screws 11, as will be understood from Fig. 2. Screws 12 extend through the ears 7^a in order to hold 55 the casing 7 in position. Window sashes are shown at 13, 14, and are normally movable

relatively to each other in the usual manner. Strips 15, 15^a, terminating flush with the upper and lower edges respectively of the casing 7, are provided for the purpose of 60 holding the sashes in proper position.

Mounted centrally within the casing 7 is a boss 16 upon which is pivotally mounted a lever 17, the lower end of which is engaged by a finger 18 carried by a revolute shaft 19. This revolute shaft is provided with an angular boss 20 which may be engaged by a key 21 for the purpose of turning the shaft.

Mounted within the casing 7 is a sleeve 21^a 70 fixed firmly in position and provided with guiding slots 22. A spiral spring 23 encircles this sleeve which is provided with an annular flange 24. Another sleeve 25 is also fixedly mounted within the casing 7 and is 75 provided with guiding slots 26. This sleeve is encircled by a spiral spring 27 which bears against a flange 28 integral with the sleeve.

The springs 27, 23 respectively bear against 80 pins 29, 30 carried by bolts 31, 32. A plate 33 is provided with openings 34 through which the sleeves 21^a, 25 extend. The plate 33 is further provided with an arched central portion 35 which engages the upper end 85 of the lever 17.

The operation of my device is as follows: The operator turns the shaft 19 by aid of the angular boss 20 and key 21 for the purpose, so as to leave the bolts either in normal position or locked, as desired. If the bolts are left in normal position, they are pressed upon by the springs 23, 27 acting upon the pins 30, 29, and when left in this position, if either sash be moved so as to move a bolt 95 opposite to one of the holes 10 in the adjacent strip 8 or 9, as the case may be, and the bolt holes in the sash 13, the sash having such bolt is locked, because the bolt slips into the bolt holes. In order to release the sashes, 100 the operator applies the key to the angular boss 20 and turns the shaft 19. This causes the finger 18 to force the lower end of the lever 17 inward (to the left according to Fig. 2). The plate 33 thereupon moves the pins 29, 30 outward, compressing the springs 105 23, 27 and withdrawing the bolts. If, now, the operator turns the shaft 19 hard to the right, according to Fig. 2, so as to hold the plate 33 in its outermost position (to the 110 right according to Fig. 2), it is obvious that the finger 18 may lock the lever 17 in this

position and that the bolts are now, for the time being, withdrawn from the bolt holes and thrown entirely out of action.

It will thus be seen that the device above described is automatic to the extent that it may be left in such condition that a movement of either sash will cause such sash to be locked, and if both sashes are moved, they may both be locked and unlocked at will by the operator. It will also be noted that the device may be left in such condition that the bolts are rendered temporarily inactive, the sashes being, in such case, free to move either independently or both together.

Having thus described my invention, I claim as new and desire to secure by Letters Patent:

1. The combination of movable sashes, a casing disposed adjacent thereto, bolts mounted within said casing and adapted to be thrust outwardly therefrom, springs for actuating said bolts, pins connecting said springs with said bolts, a plate movably mounted within said casing and adapted to engage said pins, a lever for controlling said plate, and means controllable at will for actuating said lever so as to move both of said bolts simultaneously.

2. The combination of a stationary framework, a casing mounted therein, sashes movable relatively to said casing, bolts mounted

partially within said casing and movable relatively to said sashes for the purpose of securing the latter in predetermined positions, a lever pivotally mounted within said casing and connected with said bolts for actuating the latter, a revoluble member mounted within said casing and provided with a finger for moving said lever, and means for turning said revoluble member.

3. The combination of a stationary framework, a casing mounted therein, sleeves connected with said casing and provided with slots, bolts slidably mounted within said sleeve, a sash movable relatively to said stationary framework and adapted to be held in predetermined positions by aid of said bolts, pins connected with said bolts and extending through said slots in said sleeves, springs encircling said sleeves and engaging said pins for the purpose of moving said bolts into engagement with said sashes, and means for moving said bolts against the action of said springs.

In testimony whereof I have signed my name to this specification in the presence of two subscribing witnesses.

CHARLES C. HIGGINS.
